(57) CLAIM

The ornamental design for a wearable drug delivery device, as shown and described.

DESCRIPTION

FIG. 1 is a top perspective view of a wearable drug delivery device showing our new design;

FIG. 2 is a bottom perspective view thereof;
FIG. 3 is a top plan view thereof;
FIG. 4 is a left side elevation view thereof;
FIG. 5 is a right side elevation view thereof;
FIG. 6 is a front elevation view thereof;
FIG. 7 is a rear elevation view thereof; and,
FIG. 8 is a bottom plan view thereof.
The broken lines show portions of the design that form no part of the claimed design.
